UNITED STATES PATENT OFFICE.

FREDERICK E. BICKFORD, OF ROCHESTER, NEW YORK.

CONTAINER FOR FOOD PRODUCTS.

Application filed June 30, 1926. Serial No. 119,653.

My invention relates to containers for food products, covers or caps therefor, and means for sealing the caps on the containers.

An object of my invention is to provide an improved form of container, preferably made of glass, designed and adapted for use as a pitcher from which the contents may be poured, in combination with a suitable cover or cap which may be sealed on the container 10 when the latter has been filled with its original contents.

A further object of the invention is to provide an improved form of container with a cover therefor having a seal on the exterior 15 surface of the container, in combination with an interior surface conformation of the container adapting it to seat a closure cap or cover within the container preferably at a level below the exterior seal, thereby adapting 20 the container to be repeatedly used as a bottle or holder for milk or the like after it has served its purpose as a container for the original contents.

Other objects of the invention will appear 25 hereinafter.

In the accompanying drawings:

Figure 1 is a top plan view of a cap or closure device applied to the container.

Figure 2 is an elevation partly in section 30 showing the container and a cap sealed thereon.

Figure 3 is a fragmentary sectional elevation of the container with the original sealing cap removed and an interior closure in position.

Figure 4 is an elevation of the container and its cap viewed in a direction at right angles to that of Figure 2.

Figure 5 is a fragmentary sectional view 40 on an enlarged scale showing one form of sealing means.

Figure 6 is a similar view showing a modified form of sealing means.

Figure 7 is a front elevation showing a 45 portion of the cap and sealing means.

Figure 8 is a similar view of a modification.

The container is herein shown as made of 50 glass and comprising a body portion 10 substantially cylindrical in form, above which is a top portion 11 curved inwardly intermediate its upper and lower ends to form a restricted portion or neck 12. This neck 12 may have its inner surface shaped to provide

an annular shoulder 13 which forms a seat for a closure piece or cover 14 made of paper 55 composition or other suitable material.

The container is preferably formed with a spout opening 15 in its upper end, adapting the container to be used as a pitcher from which liquid contents may be poured. 60 Diametrically opposite the spout opening 15, a handle 16 is provided, preferably integral with the container. The handle is recessed as shown in broken lines at 17 (Fig. 4) to provide a suitable hand grip. If desired, this 65 recess may be extended entirely through the handle, thereby forming an open space between the handle and the neck of the container. As shown in Figure 2, the outline of the handle is substantially in line with the 70 outer face of the body portion 10 directly beneath the handle. In other words, the handle does not protrude beyond the general outline of the container, but lies wholly within the vertical projection of the body portion 10. 75 The upper edge of the side wall of the container is thickened at α , at the side opposite the spout opening 15, to direct the contents of the container toward the spout. This thickened portion is gradually decreased 80 along the circumference of the top and merges into the normal thickness of the wall at the spout opening.

A cap or closure device 20 is adapted to be sealed on the container when the latter has 85 been originally filled with a food product or other substance. This cap, as shown, is formed from a single piece of sheet metal and comprises a circular top or cover portion to seat on the rim of the bottle, and a depending 90 peripheral flange or skirt 21. The top of the cap may be formed with a central depressed portion 22.

The skirt 21 is formed at its lower edge with an integral bead 23 which, in its original 95 form, is substantially semi-circular in cross-section, as shown in Fig. 5, and provides an annular space surrounding the container to receive a sealing material, as will presently be described. This bead is more or less flattened out during the sealing operation.

In order to provide an effective seal and at the same time provide means for readily removing the sealing medium to permit removal of the cap 20, the following means are 105 provided: A wire 24 or other element having

sufficient strength and flexibility for the purpose indicated, extends around the container within the bead 23. This wire is covered with rubber composition surrounded by a suitable woven fabric 25 impregnated with a rubber composition or like material. This fabric is in turn embedded within a sealing gasket or medium 26 preferably consisting of a rubber composition or other plastic material or substance possessing the requisite properties adapting it to serve as a hermetic seal between the cap and the adjoining wall of the container. The wire 24, as above noted, extends circumferentially around the container and its ends 27 and 28 are crossed at a notch 29 formed in the bead 23 and extend outwardly or downwardly away from the bead. A seal 30, which may be of sheet metal, unites the ends 27 and 28 and forms therewith a loop or ring in which a finger may be inserted and the seal 30 readily disconnected from the end 28 by a slight pull, leaving the seal connected with the end 27 to which it is more securely attached. This provides a handle for pulling the wire 24 and unsealing the cap from the container, as presently described.

The sealing material 25 completely surrounds the container, the wire being embedded therein and emerging therefrom at the notch 29, whereby a perfect seal is maintained. The skirt 21 is formed with a circumferential score 31 by which the metal is weakened, permitting the bead 23 with the sealing gasket therein to be torn off for unsealing the container. The score line includes an inclined portion 32 (Fig. 7) extending from the main line and terminating at the notch 29 to facilitate commencement 40 of the tearing operation.

The cap 20 is sealed to the container by compressing the sealing medium 25 against the sealing surface of the container, that is, the annular exterior surface of the container within the bead 23. This sealing may be accomplished by applying a head pressure on top of the cap while a frusto-conical hand chuck surrounding the bead 23 descends, and on account of its decreasing diameter exerts 50 a lateral or inward pressure on the entire periphery of the bead with its enclosed sealing medium. This chuck is preferably formed on its inner face with ridges or corrugations extending up and down. These ridges being forced against the bead 23 at close intervals as the chuck descends, produce corresponding corrugations in the metal of the bead while flattening the latter to a certain extent against the jar finish, thereby producing an effective seal. It will be noted that the handle 16 is located entirely below the sealing surface so as not to interrupt the circular contour of said surface, nor interfere with applying the cap and making a perfect seal.

Figure 6 illustrates a modification in which the bead is angular in cross-section, comprising flat sides 23^a and 23^b.

In order to remove the cap, the seal 30 may be grasped, as hereinbefore noted, and given 70 a pull by which the end 28 of the wire is disconnected. A continued pull on the seal or handle 30 then serves to tear or rip the bead 23 from the skirt 21, the tear commencing at the notch 29, extending along the line 32 to the main score line 31, and thence entirely around the cap. The sealing material 25 is removed with the bead, thereby unsealing the cap and permitting it to be readily lifted off 80 the container. After the bead has thus been removed, the cap may be repeatedly used for temporarily closing the container while the contents thereof are being used up.

In some instances, it may be desirable to omit the score line 31. The wire 24 with the 85 surrounding sealing material 25 may then be withdrawn from the bead, leaving the cap and bead intact. The lower edge of the bead is spaced from the side wall of the container a sufficient distance, as shown for example, in 90 Figure 2, to permit the withdrawal of the sealing gasket without tearing off the bead when the score line is omitted. The cap being thus unsealed can be readily removed and replaced. Figure 8 illustrates such a construction in which the score line and also the 95 notch 29 are omitted.

Modifications may be resorted to within the spirit and scope of my invention.

What I claim is:

1. A vessel or container open at its upper end and formed with a pitcher spout opening, and having below said spout opening an exterior circumferential sealing surface, the spout portion of the container being substantially entirely within the vertical extension of said sealing surface, and a handle opposite said spout and below said sealing surface.

2. A container for food products comprising a cylindrical body portion and a neck portion above the body portion, said neck portion being of substantially the same diameter at its upper end as said body portion and constricted intermediate its upper and lower ends, and a handle extending vertically across 115 said constricted portion and lying within the outline of the vertical projection of said cylindrical body portion.

3. A container for food products comprising a cylindrical body portion and a neck portion above the body portion, said neck portion being constricted intermediate its upper and lower ends, and a handle extending vertically across said constricted portion and lying within the outline of the vertical projection 120 of said cylindrical body portion, said container formed with a spout opening opposite said handle, said handle terminating at a point below the upper edge of the container, the latter being formed with a circumferen- 130

tial sealing surface above the handle and below the spout opening.

4. A container for food products comprising a cylindrical body portion and a neck portion

- 5 above the body portion, said neck portion being constricted intermediate its upper and lower ends, a handle extending vertically across said constricted portion and lying within the outline of the vertical projection 10 of said cylindrical body portion, said container formed with a spout opening opposite said handle, said handle terminating at a point below the upper edge of the container, the latter being formed with a circumferential sealing surface above the handle and below the spout opening, a flanged cap forming a cover for the container, and a plastic sealing material engaging said sealing surface and forming a hermetic seal between the cap 15 flange and the container.

5. The combination of a container, a cover therefor, a ring gasket of plastic material surrounding the container and forming a hermetic seal, a wire surrounding the container 25 and embedded in said gasket, said wire having its ends protruding beyond the gasket, and a seal connecting the ends of said wire.

6. The combination of a container, a cover therefor, a ring gasket of plastic material surrounding the container and forming a hermetic seal, a wire surrounding the container 30 and embedded in said gasket, said wire having its ends crossed and protruding below the gasket, and a seal connecting said ends and forming therewith a loop.

7. The combination of a container, a cover therefor comprising a top portion and a depending circumferential flange portion, a hollow bead formed on said flange portion 40 and surrounding the container, a sealing gasket of plastic material within said bead and surrounding the container, a wire embedded in the gasket and surrounding the container, said bead formed with a notch or 45 opening through which the ends of the wire protrude, and a seal connecting said ends, said seal being securely connected to one of said ends and detachable from the other end of the wire by a comparatively slight pull.

50 8. The combination of a container, a cover therefor comprising a top portion and a depending circumferential flange portion, a hollow bead formed on said flange portion and surrounding the container, a sealing 55 gasket of plastic material within said bead and surrounding the container, and a wire embedded in the gasket and surrounding the container, said bead formed with a notch or 60 opening through which an end of the wire protrudes, said cap formed with a weakened

line or score extending circumferentially thereof above said bead, whereby the bead may be torn off and the cap unsealed by pulling said wire.

9. The combination of a container, a cap 65 therefor comprising a flange portion surrounding the container, said flange being formed with a score line extending circumferentially of the container and providing a removable strip, a wire extending lengthwise of the score line, and means connecting said wire and strip whereby the latter may 70 be removed by pulling on said wire.

10. The combination of a container, a cap 75 therefor comprising a top and a depending flange surrounding the container, said flange being formed with a bead extending circumferentially around the container, said cap formed with a score line above said bead and extending lengthwise thereof, and a wire 80 within said bead and extending lengthwise thereof, said wire having a protruding end.

11. A container comprising a substantially cylindrical body portion and a restricted neck portion, the walls of said neck portion 85 being upwardly convergent from the body portion to an intermediate plane of said neck portion and thence upwardly and outwardly divergent to the upper end of said neck portion, said upper end being substantially the 90 same diameter as said body portion, the container being formed with an interior annular shoulder at or near said plane, said shoulder presenting a flat horizontal annular surface to provide a seat for a removable 95 disk cap.

12. A container comprising a substantially cylindrical body portion and a restricted neck portion, the walls of said neck portion being upwardly convergent from the body 100 portion to an intermediate plane of said neck portion and thence upwardly and outwardly divergent to the upper end of said neck portion, said upper end being substantially the same diameter as said body portion, the container being formed with an interior annular 105 flat shoulder at or near said plane to provide a seat for a removable disk cap, the container being formed with a spout opening above said shoulder, and a handle opposite the spout opening, the upper end of the handle terminating at a point below the upper end of the container, the latter having a circular circumferential exterior surface to fit the flange portion of a cover piece when the latter is 110 placed on the container.

Signed at New York, in the county of New York and State of New York, this 21st day of June, 1926.

FREDERICK E. BICKFORD.
